CONCRETE BOX JOINT

Thornton Hamlin, Pasadena, and John Hiram
Hood, South Pasadena, Calif.

Application December 31, 1937, Serial No. 182,772

10 Claims. (Cl. 72—38)

This invention relates to building structures, the elements of which are made of relatively heavy materials, and particularly to a joint between two structural building elements.

5 It is an object of our invention to provide an interlocking joint for structural building elements of such a character that the weight of one element will act to prevent displacement in any direction of the joined elements with

10 respect to each other.

It is a further object to provide such an interlocking joint which shall be of simple yet effective and sturdy design.

15 It is a further object to provide a joint of such design that the engaging surfaces on the interlocking elements may be readily and inexpensively formed when casting such elements from concrete or other similar material.

20 It is a further object to provide such an interlocking joint that the weight of one of the joined elements and the weight of any bodies carried thereby will act to draw the elements closely together and securely lock them in position.

25 To illustrate our invention, we have disclosed it as applied to a rectangular concrete box structure such as is used for a burial vault. It will be understood, however, that the joint of our invention can be used in other concrete structures, such as incinerators, or in structures of buildings of concrete, stone, iron, wood, or other material, wherein it is desired to employ a self-locking joint utilizing the weight of one of the joined elements and of bodies superimposed

30 thereon to lock together the two elements.

35 In the drawing,

Fig. 1 is a perspective view of a burial vault constructed in accordance with our invention, some portions of some of the box members being broken away to better disclose the details of the

40 design of the joint;

Fig. 2 is a side elevational view of the vault; and

Fig. 3 is an end elevational view of the vault.

45 A vault of the type shown in the drawing is used customarily at the bottom of an earthen grave to receive the coffin and protect it from the disintegrating action of the earth. Concrete makes a satisfactory material for such a vault because of its resistance to decay. Because of the great weight of concrete, a vault of this material must be constructed of many small parts, cemented together in the grave, which will offer weak resistance to the pressure of the surrounding and superincumbent earth, or it must be constructed of a few very heavy parts, which are

difficult to assemble in position and lock against relative movement, in such relationship that the vault will not be crushed by the weight of the earth upon it. The vault shown in the drawing is constructed of a few very heavy parts, and these are closely locked together against lateral and vertical earth pressure by the use of joints constructed in accordance with our invention.

A bottom slab 11 is lowered into the grave and rests upon the earth in the bottom thereof. One-piece side walls 12 and 13 are then placed in position, as shown. At the ends of each of these side walls there is formed integrally with the main portion of the wall a projection or tongue 14, which extends longitudinally from the end of the wall approximately midway between the top and bottom thereof and is of the same thickness as the wall. This tongue is formed with a top face 15, which is inclined upwardly and outwardly from the end of the side wall, a bottom face 16 parallel to the top face 15, and a vertical end face 17. There is also formed on the vertical face of each end of each side wall 12 and 13 a ridge 18, V-shaped in horizontal cross section, which extends from the top to the bottom of the side wall except where it is interrupted by the tongue 14. The end face 17 is vertical over end faces 19 of the bottom slab 11.

End walls 20 are then lowered into position. Each of these end walls is cast with a slot or recess 21 extending across end face 22. Upper face 23 of this slot and lower face 24, which is parallel thereto, are inclined upwardly and outwardly. The vertical depth of the slot is slightly greater than the vertical depth of the tongue 14, and the horizontal depth of the slot is equal to the thickness of the side wall 12. The slot 21 is disposed approximately midway of the top and bottom edges of the end wall 20. The inner face of the end wall is also formed at each end 40 with a vertical groove 25, V-shaped in horizontal cross section and extending from the top to the bottom of the end wall except where it is interrupted midway of its length by the slot 21. This groove is of the same shape and size as the ridge 45 18 on the end of the side wall 12 and is disposed adjacent the end face 22 of the end wall 20.

As an end wall is lowered into place it is not directly above the position it is to finally occupy upon the bottom slab 11, but is displaced horizontally beyond the end of the bottom slab by a distance equal to its own width. When, during the lowering movement of the end wall 20, the slots 21 are horizontally opposite the tongues 14, the upper faces 23 of the slots are caused to en-

gage and rest upon the top faces 15 of the tongue by giving the end wall a slight horizontal movement toward the ends of the side walls 12 and 13. When the end wall is now permitted to settle under the action of gravity, it moves downward and toward the side walls, under the controlling influence of the engaging surfaces 17 and 23, until the bottom edge of the end wall rests upon the bottom slab and the faces of the groove 25 have contacted the faces of the ridge 18. When both end walls have been thus assembled with the side walls, the cover slab 26 is placed in position. As shown, it is made in three sections and rests loosely upon the side and end walls. Whether the cover is made in one piece or in two or more sections, and whether it rests loosely upon the box walls or is provided with some means for preventing lateral displacement, is, of course, entirely a matter of structural design and preference to meet a given set of conditions. Similarly, means may be provided, if deemed desirable or necessary, to prevent lateral displacement of the walls of the box with respect to the bottom slab 11.

25 When the bottom, walls, and top are assembled as shown, it is apparent that the weight of the ends, the cover, and earth or other material on top of the cover, tends to force the end wall into close contact with the ends of the side walls and 30 to lock the end wall against horizontal displacement either outwardly away from the ends of the side walls or transversely of the ends of the side walls. The interlocking faces 23 and 15 are the means by which this weight prevents the 35 former displacement, and it is by the combined action of these faces and of the mating groove 25 and tongue 18 that this weight is effective to prevent the latter displacement.

The essence of our invention is the interlocking 40 joint so constructed that, when in proper position, the weight of one of the joined members tends to hold that member against displacement horizontally in any direction with respect to the other member. While we have described the 45 joined elements or members as vertically disposed, and have so referred to them in the claims, we wish it understood that this is for convenience and brevity of description only, and that if either or both of the joined members are disposed in 50 any position between the horizontal and vertical, it is still possible that a component of the force of gravity acting upon the mass of one of the members may be effective to hold the joined members in locked relationship. Even if one of the 55 members is disposed horizontally, it is possible for some force other than gravity to act to hold the joined members in interlocked relationship.

It will be apparent that many changes can be 60 made in the details of construction of the embodiment of our invention described above without departing from the principles thereof. For example, the bottom slab, for convenience of handling, may be made of a plurality of sections. The 65 grooves 25 and mating ridges 18 may be of arcuate, rectangular, or other outline in cross-section, instead of V-shaped as shown and described herein.

While we have described and shown one embodiment of our invention, we desire not to be 70 limited to this embodiment, but define and set forth our invention in the following claims.

We claim as our invention:

1. A structural assembly, comprising: a first 75 vertical plate having a vertical groove on its first side face and a transverse recess opening on said

first side face, the upper face of said recess sloping upwardly and outwardly; and a second vertical plate having a first projection extending longitudinally from the end of said second plate and mating with said groove and adapted to prevent 5 horizontal displacement of said first plate transversely of said second plate, and having a second projection extending longitudinally from its said end face adapted to enter said recess, its upper face sloping upwardly and outwardly to mate with 10 the upper face of said recess and adapted to prevent displacement of said first plate with respect to said second plate either vertically downward or horizontally toward or from said second plate.

2. A structural assembly, comprising: a first 15 vertical plate element having a recess formed on its inner face, the upper face of said recess sloping upwardly and outwardly; and a second vertical plate element having a projection formed on one of its ends, said projection being adapted to 20 enter said recess and formed with its upper face sloping upwardly and outwardly, the end of said second plate element and the inner face of said first plate element being formed one with a second projection and the other with a mating depression adapted to prevent displacement of said first plate element transversely of the end of said second plate element.

3. A structural assembly, comprising: a first 25 vertical plate formed with an inclined parallel walled slot extending across one of its end faces and upwardly from its first side face to its second side face, and a vertically disposed groove on its first side face adjacent said one of its end faces, said groove extending from the top of said first 30 plate to and communicating with said slot, and from said slot to the bottom of said first plate; and a second vertical plate adapted to be joined at one of its ends to said first vertical plate adjacent the said end face of said first vertical 35 plate and in horizontally angular configuration with respect to said first vertical plate and with the face of its said end abutting said first side face of said first plate, said second vertical plate being formed with a tongue projecting from its 40 said end face shaped to snugly fit in said slot of said first plate and being further formed with a projecting vertically disposed ridge shaped in cross section to snugly fit in said groove of said 45 first plate.

4. A structural assembly, comprising: a first 50 vertical plate formed with an inclined slot across one of its end faces, and a vertical groove disposed adjacent said end face and on that one of its side faces upon which opens the lower end of said slot; and a second vertical plate formed with a tongue on one of its end faces, said tongue 55 projecting longitudinally from said second plate and having the same shape and substantially the same size as the said slot and being inclined upwardly from said second plate, said second plate being also formed with a vertically disposed ridge on its said end face adapted to mate with said vertical groove.

5. In a rectangular box: a pair of vertical side 60 walls; and a pair of vertical end walls, each of one of said pairs of walls being provided on each of its end faces with a longitudinally extending supporting tongue having top and bottom faces which slope outwardly and upwardly in a 65 direction longitudinally of said wall and are horizontal in transverse section, and each of the other of said pairs of walls being provided with a transverse recess in each of its end faces adapted to snugly fit one of said tongues, and each 70 75

of one of said pairs of walls being provided in the vicinity of each of its ends with a vertical groove, and each of the other of said pairs of walls being provided in the vicinity of each of its ends

5 with a projection adapted to engage one of said grooves, said grooves and projections being adapted to prevent horizontal displacement of each of the one of said pairs of walls in either direction transversely of the end of the adjacent one of the

10 other of said pairs of walls.

6. A structural assembly of concrete slabs, comprising: a first vertically disposed slab cast with a parallel walled slot across one of its end faces, the upper and lower parallel walls of said 15 slot being horizontal in transverse section in a direction longitudinal of said slab and sloping in a direction transverse of said slab downwardly toward the inner side face of said slab; and a second vertically disposed slab cast with a tongue 20 projecting longitudinally from one of its ends and having substantially the same shape and size as the said slot and adapted to mate therewith, the said slabs being cast with engaging surfaces adapted to prevent horizontal displacement of 25 said first slab transversely of the end of said second slab in either direction.

7. A structural assembly of concrete slabs, comprising: a first vertically disposed slab cast with a parallel walled slot across one of its end faces, 30 the upper and lower parallel walls of said slot being horizontal in transverse section in a direction longitudinal of said slab and sloping in a direction transverse of said slab downwardly toward the inner side face of said slab; and a second vertically disposed slab cast with a tongue 35 projecting longitudinally from one of its ends and having substantially the same shape and size as the said slot and adapted to mate therewith, the said slabs being cast with vertically elongated en- 40 gaging surfaces extending from the top to the bottom of said slabs adapted to prevent horizontal displacement of said first slab transversely of the end of said second slab in either direction.

45 8. In a concrete structure: a first vertically disposed plate cast with a slot across one of its end faces, the upper and lower walls of said slot being parallel and horizontal in transverse sec-

tion in a direction longitudinal of said slab and sloping in a direction transverse of said slab downwardly toward the inner face of said slab, and further cast with a vertically disposed groove, V-shaped in cross section, on its inner side face adjacent its said end face; and a second vertically disposed plate cast with a tongue projecting longitudinally outwardly from one of its end faces, said tongue being of substantially the same horizontal length and transverse vertical 10 sectional shape and dimensions as the said slot, and further cast with a vertically disposed ridge of substantially the same cross sectional shape and size as the said groove, said ridge projecting outwardly from said end face of said second plate. 15

9. In a concrete structure: a first vertical wall element; and a second vertical wall element, the two elements being formed in casting, the one element with a supporting surface inclined to the horizontal in a direction longitudinal of one of 20 said elements, and horizontal in transverse section in a direction perpendicular to said longitudinal direction and the other with a mating inclined supported surface, the one surface extending longitudinally of its element and the other extending transversely of its element, the two elements being formed on the inner side face of one element and the end face of the other element with vertically slidably engaging surfaces additional to said supporting and supported surfaces and adapted to prevent horizontal displacement of one element transversely of the end of the other element in either direction. 25

10. In a concrete structure: a first vertical wall element; and a second vertical wall element, the 30 two elements being formed in casting, the one element with an inclined supporting surface and the other element with a mating inclined supported surface, the one surface inclined longitudinally of its element, and the other surface inclined transversely of its element, the two elements being formed with vertically slidably engaging surfaces, the horizontal sectional lines of the said vertically slidably engaging surfaces being set at an angle to the longitudinal lines of 35 one of said elements. 40
